UNITED STATES PATENT OFFICE

2,050,632

SIGNAL TRANSMITTER

Harry S. Smith, Needham, Mass., assignor to The Gamewell Company, Newton Upper Falls, Mass., a corporation of Massachusetts

Original application January 24, 1931, Serial No. 511,339. Divided and this application August 7, 1934, Serial No. 738,847

5 Claims. (Cl. 40—70)

This invention relates to signal transmitters, and more particularly to variable signal initiating station transmitters involving manually operable members for varying the characteristics of signals, both as to their component parts, and as to 5 cycles of operation or repetition of the signals formulated thereby.

In signal transmitters of this type, the manually operable members for varying the characteristics of the signal are usually provided with 10 indicating means to indicate the particular characteristic of the signal for which each individual member is at any time set, and it is desirable that operation of any one member will not alter the setting, and hence the indication of another 15 member.

It is therefore an object of this invention to provide manually operable members for varying the characteristics of the signal arranged so that, 20 when in upset position, they will be disengaged from the characteristic varying mechanism of the transmitter to prevent unintended actuation.

Another object is to provide means whereby engagement of such members with said mechanism will be maintained throughout all set 25 positionings thereof.

Another object is to provide locking means for 30 positively retaining, in upset position, such members and their associated indications throughout such disengagement.

A signal transmitter of a type in which this invention may be employed is fully shown and described in the co-pending application of Nathan H. Suren and the present applicant, filed January 24th, 1931, Serial No. 511,339, for Signal transmitters, upon which there has issued Patent No. 1,986,026, dated January 1st, 1935, of which this is a division.

Detailed description of the mechanism of such 40 a transmitter will therefore be herein omitted.

For the purpose of enabling this invention to be readily understood, an embodiment thereof is hereinafter described, and is shown in the annexed drawing indicating portions of a transmitter such as described in the above mentioned co-pending application and in which:

Figure 1 is a front elevation of a signal transmitter embodying the invention;

Fig. 2 is a detail view of one of the digit indicator plates; and

Fig. 3 is a fragmentary vertical section taken on the line 3—3 of Fig. 1 showing certain of the parts positioned as for the digit "5".

Reference characters applied to the parts 55 shown by the drawing of this application corre-

spond to those applied to corresponding parts on drawings of the above mentioned co-pending application, to facilitate reference thereto.

Referring to the embodiment of this invention illustratively indicated in the accompanying drawing, the signal transmitter shown may be enclosed in a suitable casing which is generally indicated in Fig. 1, in which the front panel 21 has detachably secured thereto an annular disc 22. This disc constitutes a face plate or dial 10 having associated therewith a plurality of knobs 23, 24, 25, 26, 27, 28 and 29, by means of which the device may be operated and controlled.

The knob 23 controls the round setting mechanism, the knobs 24, 25, 26 and 27 control the several digit plates and their associated mechanism, the knob 28 controls the restoring mechanism, and the knob 29 controls the starting mechanism. Above the knob 23, the face of the dial 22 is provided with the numerals 1, 2, 3 and 4, 20 which designate the "rounds". Operable by the knob 23, is a pointer 30, which indicates the number of rounds for which the transmitter is set. The knobs 23, 24, 25, 26 and 27 are rotatable, while the knobs 28 and 29 are manually movable 25 toward the dial 22.

The knobs 24, 25, 26 and 27 are arranged in a horizontal row. Above each of these knobs there are openings 20 in the dial, through which numerals on the digit plates may be viewed.

The frame of the transmitter mechanism includes the two spaced frame plates 31 and 32. Interposed between the dial 22 and the front frame plate 31, are digit indicator plates 35, 36, 37 and 38, in the form of annular discs of relatively thin sheet metal, provided circumferentially with numerals from "0" to "9", inclusive, as shown in Fig. 2.

The digit plates are mounted on and rotated by the respective shafts as shown in Fig. 3, where 40 dial 37 is shown on its shaft 41 and rotated therewith by pin 452 carried by the arm 442 forming part of collar 432 which is secured to the shaft 41.

The shafts extend through bushings in the dial 45 22 and the knobs 24, 25, 26 and 27 are respectively mounted on the outer ends of said shafts.

Referring to the mechanism indicated by Fig. 3, which is generally representative of that associated with knobs 25, 26 and 27—the bushing 50 462, through which shaft 41 extends, is secured in the dial 22 and has formed therein an opening 472 for the reception of the end of the pin 452. This opening is so located that, when the end of the pin 452 is disposed in said opening, 55

the digit plate 37 will be positioned so that the numeral "0" carried thereby will register with the dial opening 20.

The shaft 41 has an end 48 projecting through the frame plate 32, and a leaf spring 50 secured to said plate 32 bears against said end 48 so as to urge endwise movement of the shaft toward the dial 22.

As described in greater detail in the hereinbefore mentioned co-pending application, the gears 66, 67, 68 and 69 form part of the digit setting mechanism and each is adapted to be rotated by its respectively associated knob 24, 25, 26 or 27.

15 The gear 66 carries a pin 117 which normally engages a stop 118 secured to the frame plate 31, and also carries a second pin 119 which is disposed in the path of a pin 120 carried by gear 67; gear 67 also carries a second pin 121 which is disposed in the path of a pin 123 carried by gear 68; and gear 68 also carries a second pin 122 which is disposed in the path of a pin 124 carried by gear 69.

20 Gear 69 is urged to rotate in a clockwise direction (when looking toward the front of the mechanism) by a spring 141, and, through engagement of the pins carried by the gears 66, 67, 68 and 69, the gears 66, 67 and 68 are also urged by said spring 141 to rotate in said clockwise direction until pin 117 carried by gear 66 engages the stop 118.

25 From the foregoing it will be apparent that rotation of gear 66 by knob 24 will also cause corresponding rotation of all the remaining gears 67, 68 and 69; and that rotation of gear 67 or 68 by knob 25 or 26 will correspondingly cause rotation of the remaining gears between it and the spring 141.

30 The gears 66, 67, 68 and 69 are rotated by their respective knobs through gears secured to the respective shafts, such as the gear 57 on shaft 41, as shown in Fig. 3.

35 This gear 57 is secured to the shaft 41 in such position that, when the shaft 41 is moved endwise against the tension of the leaf spring 50 a sufficient distance to withdraw pin 452 from the opening 472 in bushing 462 so as to permit rotation thereof, the teeth of said gear 57 will be in mesh with the teeth of gear 68.

40 Endwise movement of shaft 41 incidental to entrance of pin 452 into the opening 472 carries gear 57 out of engagement with the gear 68. This permits rotation of gear 68 without thereby causing rotation of the shaft 41 and the indicator 37.

45 Such disengagement of the gears on the individual shafts from the respective gears 67, 68 and 69 permits rotation of any of the gears 66, 67 or 68 without moving any of the respectively succeeding digit plates 36, 37 or 38 from their 50 "0" position.

55 It is deemed expedient, for reasons well understood by those skilled in this art, that setting of the gears 66, 67, 68 and 69 shall be accomplished in a predetermined sequence, starting with gear 66 and continuing in the order named, to the end that the digit plates shall correctly indicate the number for which the mechanism is set; hence a sleeve 56 is mounted on the shaft 41 between the collar 432 and the gear 57 and is provided with a laterally projecting arm 561 having an opening therein, through which projects a rod 59 carried by the frame plate 32. Depending from the lower side of the sleeve 56 is a downwardly extending lug or tip 562 which is adapted to mesh 60 with the teeth of the gear 67 when the shaft 41

is moved endwise to a position where the gear 57 carried thereby meshes with the gear 68.

Corresponding sleeves with extending lugs are also provided for the shafts associated with knobs 25 and 27.

5 As a result of the structure just described, a setting of the knob 24 is locked against revision upon movement of the knob 25 away from its "0" position, that of the knob 25 by the knob 26, and that of the knob 26 by the knob 27.

10 From the foregoing it will be seen that when shaft 41 has been rotated so that the digit plate 37 displays the numeral "0" through opening 20 in dial 22, the pin 452 will be positioned for entering the opening 472, and the leaf spring 50 will thereupon move the shaft 41 endwise. The pin 452 entering the opening 472 thus locks the shaft against rotation until again moved endwise against the tension of the spring 50, as by pressing in on knob 26.

15 Such endwise movement of shaft 41 also carries the gear 57 out of mesh with gear 68 and carries the extending lug 562 out of engagement with the teeth of gear 67.

20 Disengagement of lug 562 from the gear 67 permits rotation of this gear by the knob 25, and positioning of gear 57 out of mesh with gear 68 permits such rotation of gear 67 without thereby moving digit plate 37 from its normal or "0" position.

25 The shafts associated with knobs 25 and 27 of Fig. 1, are correspondingly arranged for endwise movement and each carry a gear and a lug corresponding to the gear 57 and lug 562 on shaft 41 shown in Fig. 3.

30 The shaft associated with knob 24, in the particular embodiment of the invention shown in Fig. 1, need not be so arranged for endwise movement, as the digit plates are set from left to right when setting the mechanism for the transmission of any number, and there is therefore no gear of sequential precedence for this shaft to either lock or disengage from.

35 Although this invention has been described as forming part of a specific mechanism,—it should be understood that this is illustrative only, and for the purpose of making clear the nature and objects of the invention, as it is believed that the invention, as defined by the following claims, is not limited to any specific structure, except insofar as such limitations are included within the terms of the claims.

40 Having thus described my invention, what I claim as new, and desire to secure by Letters Patent of the United States of America is:

I claim:

45 1. In a signal transmitter, the combination with a frame, of a dial, a digit plate having an opening formed centrally therein and a second opening formed therein in offset relation to the first opening, a shaft mounted for rotary and also rectilinear movement, one end of said shaft projecting through said first opening and through a bushing in the dial, the other end of said shaft projecting through an opening in the frame, a pin carried by the shaft in spaced relation thereto and extending through the second opening in the digit plate, an opening formed in the dial bushing for receiving the end of the 50 pin when the digit plate is in a predetermined position, and resilient means for urging the shaft in the direction for causing the pin to bear against said bushing.

55 2. In a signal transmitter, the combination

with a frame of a dial carried by the frame, a digit plate associated with the dial, said digit plate comprising an annular disc having an opening formed centrally therein and a second opening formed therein in offset relation to the first opening, a shaft mounted for rotary and rectilinear movement, said shaft projecting through said first opening and through a bushing in the dial and being provided with an operating knob, the other end of said shaft being reduced in diameter and projecting through an opening in the transmitter frame, a crank arm carried by said shaft, a pin projecting from the crank arm in substantial parallel relation to the shaft and extending through the second opening in the digit plate, an opening formed in the dial bushing for receiving the end of the pin when the digit plate is in a predetermined position, and resilient means for urging the shaft in the direction to cause the pin to enter the opening in the bushing.

3. In a signal transmitter, the combination with a frame, of a dial, a shaft mounted for rotary and also rectilinear movement, one end of said shaft projecting through said dial, the other end of said shaft projecting through an opening in said frame, an indicating member movable to any of a plurality of positions in response to rotation of said shaft, a pin carried by said shaft in spaced parallel relation thereto, an opening formed in said dial for receiving the end of said pin when said indicating member is in a predetermined position, and resilient

means for urging said shaft in the direction for causing said pin to enter said opening.

4. Indicator mechanism comprising a plurality of independently rotatable indicating members each having a normal position, setting members for the respective ones of said indicating members operable in a predetermined sequence for setting respective ones of said members to any of a plurality of positions, certain of said setting members each comprising a shaft 10 mounted for rotary and also rectilinear movement, resilient means for urging rectilinear movement of said shaft in one direction, means for permitting said movement of said shaft by said resilient means only when the indicating 15 member associated therewith is in its normal position, and locking means rendered effective upon rectilinear movement of said shaft, in a direction opposing the urge of said resilient means, for locking against rotation any shaft 20 previously operable in said sequence.

5. Indicator mechanism comprising a plurality of independently rotatable indicating members each having a normal position, individual means operable in a predetermined sequence for setting respective ones of said members to any of a plurality of positions, and locking means rendered effective upon operation of respective ones of said setting means from its normal position for locking against operation any setting 30 means previously operable in said sequence.

HARRY S. SMITH.
